CLAIM

The ornamental design for a washing machine agitator, as shown and described.

DESCRIPTION

FIG. 1 is a top isometric view of a washing machine agitator showing my new design;

FIG. 2 is a top plan view thereof;

FIG. 3 is a side elevational view thereof;

FIG. 4 is another side elevational view thereof;

FIG. 5 is a sectional view thereof, taken along lines 5—5 in FIG. 3; and

FIG. 6 is a sectional view thereof, taken along lines 6—6 in FIG. 3.

The environmental structure shown in broken lines in FIGS. 1, 3 and 4 is for illustrative purposes only and forms no part of the claimed design.

FIG.1

FIG. 2

FIG. 3

FIG. 5

FIG. 6

FIG. 4
